FASTENING DEVICE FOR MOPS, BRUSHES,
AND THE LIKE

John W. Brintnall, Alameda, Calif.

Application May 2, 1939, Serial No. 271,353

5 Claims. (Cl. 306—1)

The invention relates to fastening devices such as commonly used for securing mops and similar articles to the end of a stick handle.

An object of the present invention is to provide a fastening device of the character described by means of which a large variety of types of cleaning means such as mops, brushes, chamois skins, sponges, cleaning cloths and the like may be easily and quickly attached to a stick handle, whereby a single handle or a set of different size and length of handles may be used with a plurality of such cleaning means.

Another object of the invention is to provide a fastening device of the character described which will attach any of the above mentioned cleaning means to a stick handle in such a manner that the handle and attaching device will be substantially completely covered and removed from contact with the surface to be cleaned, and the cleaning means most effectively disposed with respect to the handle for convenient use.

A further object of the invention is to provide a gripping device of the above character which may be constructed of a minimum number of sturdily formed parts whereby the device will have a substantially unlimited long life of usefulness and the operation thereof will be substantially positive and fool-proof.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a side elevation partly in section of a fastening device constructed in accordance with the present invention.

Figure 2 is a front view of the fastening device illustrated in Figure 1.

Figure 3 is an end view of the fastening device.

Figure 4 is a cross-sectional view of the fastening device taken substantially on the plane of line 4—4 of Figure 1.

Figure 5 is a side elevation of the fastening device shown partly in section and operatively associated with a stick handle and a brush.

Figure 6 is a front elevation of the fastening device shown operatively associated with a stick handle and a mop.

Figure 7 is a side elevation partly in section of

the device shown operatively associated with a handle and a sponge.

Figure 8 is a front elevation of a modified form of holding means for the device.

Figure 9 is a cross-sectional view of the holding means illustrated in Figure 8 and is taken substantially on the plane of line 9—9 of Figure 8.

The fastening device of the present invention is adapted for use with a customary type stick handle for associating with the handle and for attaching thereto various types of cleaning implements, such as mops, brushes, cloths and the like, and is so arranged that the fastening device may be readily adjusted on the handle for securing the cleaning implement in place. To this end I provide a supporting member which may be clamped to the handle at adjusted longitudinal positions thereon and a holding means which is carried by the member and which cooperates with the end of the handle for clamping the cleaning implement in place. The latter means is so constructed to receive an ordinary mop, brush, chamois skin, sponge, dust cloth or the like.

In the preferred form of the invention illustrated in Figures 1 to 7, the supporting member 11 consists of a pair of longitudinally spaced ring members 12 and 13 which are provided with central openings 14 and 16 for accommodating and receiving a customary wooden stick handle 17. The members 12 and 13 are held in longitudinally fixed position by means of a pair of longitudinal supporting members 18 and 19, here shown of wire, which are welded or otherwise secured to the members 12 and 13. Also carried between the members 12 and 13 is a longitudinal guide 21, preferably of non-circular cross section such as the rectangular bar here shown, and which is secured as by welding or the like at its opposite ends to the end plates 12 and 13. The guide 21 is inclined longitudinally to the longitudinal axis of the handle 17 and the longitudinal aligned axis of the openings 14 and 16, and carried on the guide is a sliding member 22 which is formed with a pair of jaw faces 23 and 24 which engage longitudinal sides of the handle between the members and upon sliding of the member 22, force the handle against the opposite sides 25 and 26 of the openings. The slide member 22 is preferably of sheet metal which is stamped and formed to provide a bearing 27 slidably engaged on the guide and an outwardly extending handle portion 28 to facilitate the longitudinal movement of the slide member along the guide. By rea-

son of the taper of the guide, the device may be used with various diameter handles and also with handles of various cross-sectional shape. To further hold the supporting member against longitudinal movement on the handle, the opening sides 25 and 26 are preferably formed with sharp edges adapted to cut into the handle and as here shown, such sides are provided with a plurality of teeth 29 and 31 which upon forcing 10 of the handle thereagainst, pierce or bite into the engaged surface of the handle.

The means for fastening the cleaning implement to the handle here includes a wire loop member 32 which extends longitudinally from 15 the supporting member 11 and is so related to an adjacent end 33 of the handle as to cooperate with such end for holding the cleaning implement in place. The member 32 may, as here shown, be formed of a single length of 20 wire and may be integrally associated with the longitudinal supporting members 18 and 19. Such is the present construction, wherein a single length of wire is used and which is folded from an intermediate portion 34 of its length 25 into a pair of spaced parallel legs or sides 36 and 37 and which sides extend through openings in the end member 12 and terminate at the member 13. A portion 38 of each of such sides extends generally longitudinally from the member 12 and terminates in its outer end 39 in a laterally inclined portion 41. The portion 46 terminates in the portion 34 aforementioned and which extends at right angles to a common plane in which the portions 38, 41, 43 and 46 30 are contained. Each of the sides 36 and 37 of the loop member is provided with the aforementioned portions and the several portions on one side are substantially identical to and parallel with the respective portions on the other.

40 As will be seen in Figure 2, the sides 36 and 37 of the holder are spaced apart by a distance somewhat greater than the diameter or width of the handle. Similarly, the transverse dimension of the holder between the end point 42 and the cross-piece 34 (see Figure 1) is greater 45 than the diameter or thickness of the handle. In this manner the holder forms what may be conveniently referred to as a transverse or horizontal loop which encircles a majority of the circumference of the handle end and accordingly the handle end may extend completely through such loop without engagement with any of the portions of the loop above enumerated. This feature is of considerable importance in 50 accommodating the holder to various types of cleaning devices. Particularly is this the case when a flexible cleaning device such as a mop or cloth or sponge or the like is used. For example, with 55 reference to Figure 6, wherein a mop 47 is shown in conjunction with the holder, an intermediate portion 48 of the mop is mounted across the loop so that the mop strands are engaged under the sides 43 of the loop and then the end 33 of the handle is pressed firmly against such intermediate portion, so as to confine the mop strands between the handle end and the loop sides 43. With a normal size mop the handle end may be 60 extended beyond the plane of the loop sides 43, such as illustrated in Figure 6, so as to completely 65 submerge the holding loop and the handle end in the mop. In this manner the loop portions and the handle end are both completely removed from direct contact with the surface to be cleaned. In the case of a sponge, such as illustrated in Figure 7 where a cylindrical type

sponge 49 is disclosed, a part of the sponge body is drawn into the loop between the sides 36 and 37 so that in extending the handle end against the sponge, the latter will be clamped between the handle end and the cross-piece 34 of the 5 loop and all of the loop side portions completely embedded in the sponge. It will be noted in this connection that the face of the sponge is inclined at an angle to the axis of the handle so that the sponge is most effectively positioned for 10 convenient use. Another use for the device is in the holding of a brush 51, such as illustrated in Figure 5. The brush here illustrated is of standard form, including a brush back or support 52 and bristles 53 and in attaching the brush, the 15 latter is inserted into the loop so that the brush back is confined between the sides 41, 43 and 46 of the loop, which define a substantially rectilinear socket for receipt of the brush back. The side 46 and the cross-side 34 are embedded with- 20 in the bristles so that no part of the holder is exposed. The brush is securely held in the aforementioned position by the engagement of the handle end 33 and against the back 54 of the brush. While a mop and sponge and brush have 25 been illustrated, it will be readily understood that various other types of cleaning implements such as chamois skins, dust cloths and the like may be attached in like manner.

To facilitate the attachment of the aforementioned 30 cleaning means, the guide 21 preferably tapers inwardly towards the axis of the handle in the direction of the end 13 of the supporting member, that is away from the holder 32. This is desirable for in drawing the slide 22 towards 35 such end, the supporting member will be urged in a direction increasing the clamping pressure of the handle end and holding loop.

A modified form of supporting member 11' has 40 been illustrated in Figures 8 and 9. As there shown the supporting member is composed of a pair of half-sections 56 and 57 which are provided with circular longitudinal recesses 58 and 59 adapted to engage and embrace opposite longitudinal sides of the handle 17'. The sections 45 56 and 57 are identical in form and each provided with side wing portions 61 and 62, through which are engaged screws 63 and 64 adjusted by wing nuts 66 and 67 for clamping the half-sections 50 in place on the handle. The sections are 55 further provided with longitudinal recesses 68 in which are carried the longitudinal sides 38' and 37' of the wire loop holding member. Such wire sides may be spot-welded or otherwise conveniently fastened in the recesses 63. The construction 60 of the loop holder in this form of the invention is the same as the loop holder described in connection with the preferred form of the invention and is therefore, omitted in the showing of the modified form and in the description of such 65 modified form. In using this modified type of holder, it will be understood that the wing nuts 66 and 67 are loosened to permit longitudinal adjustment of the holder, so as to clamp a cleaning implement of the character described against 70 an end 33' of the handle and then the wing nuts are retightened to secure the assembly in place.

It will now be clear that the fastening device of the present invention is operable to quickly and easily attach various types of cleaning means as 75 above described to a stick handle, and whereby a single handle or a set of different size, shape or length of handles may be used with a plurality of such cleaning means. It will further be understood that while I have described the present 75

holding device in conjunction with various types of cleaning means, the device may be used for fastening or holding in place on or in assembly with a handle of the character herein described, 5 a large variety of articles other than above referred to.

I claim:

1. The combination with a stick handle, means for fastening to the handle a mop or brush or 10 the like comprising a member adapted for clamping on said handle adjacent one end thereof, a wire member providing a pair of sides each secured at one end to said member and each formed with a longitudinal part, a contiguous 15 laterally inclined part, a part contiguous and at substantially right angles to said second part, a part contiguous and at substantially right angles to said third part and approximately parallel to said second part, said first, second, third and 20 fourth parts being in substantially a common plane and substantially parallel to the corresponding parts of the other wire side, and a fifth part extending at substantially right angles to said plane and connecting the outer ends of said 25 fourth part.
2. In a device of the character described, a stick handle, means cooperating with the end of said handle to secure a mop or broom or the like thereto, and means for securing said first 30 means to the handle in adjusted longitudinal position, comprising, a pair of longitudinally spaced ring members surrounding said handle, means holding said rings longitudinally spaced, a longitudinal guide extending between said 35 rings and inclined to the axis of said handle, and means slidably carried by said guide and engaging a side of said handle for urging the latter against one side of said rings, one of said ring sides being formed with a sharpened edge for 40 piercing and holding the engaged side of said handle.

3. In combination with a stick handle a member adapted to engage opposite longitudinal sides of said handle, a longitudinal guide carried by said member inclined to the longitudinal axis of said handle, slide means carried by said guide and engaging a side of said handle for urging the latter against the opposite side of said member, and teeth on said last named member side for 5 piercing and holding the engaged side of said handle.

4. A device for attaching various cleaning means to a stick handle, comprising, a supporting member composed of a plurality of sections adapted to engage opposite sides of said handle adjacent an end thereof, a clamping screw for 10 fixing said sections on said handle, and a wire member including a pair of longitudinal sides secured to said sections and terminating in a transversely extending loop portion surrounding a part of the end of the handle and cooperating 15 therewith for securing said cleaning means therebetween.

5. A cleaning means holding device for a stick handle comprising, a clamp member including a pair of sections having opposed recesses for fitting about opposite sides of said handle and opposed lateral extending portions, screws carried by said portions at opposite sides of said handle for clamping said sections to the handle, said sections each having a longitudinal recess, a wire 20 member having a pair of substantially parallel longitudinal sides engaged in said longitudinal recesses and extending longitudinally from said sections, the outer ends of said sides terminating in a connecting portion encircling a part 25 of the periphery of said handle and cooperating with an end of said handle for clamping a cleaning means therebetween.

JOHN W. BRINTNALL. 40
